United States Patent

Des. 242,196
Patented Nov. 9, 1976

242,196

CORNER CABINET

John P. Salsgiver, 29 Ethan Allen Drive,
Acton, Mass. 01720

Filed Dec. 23, 1974, Ser. No. 536,018

Term of patent 14 years

Int. Cl. D6—04

U.S. Cl. D6—167

FIG 1

FIG 3

FIG. 1 is a perspective view of a corner cabinet showing my new design.

FIG. 2 is a view in right side elevation; the left side elevation being equal and opposite, and

FIG. 3 is a view in right rear elevation; the left rear elevation being equal and opposite thereof.

I claim:

The ornamental design for a corner cabinet, as shown and described.
